UNITED STATES PATENT OFFICE.

PAUL C. SCHROEDER, OF CHICAGO, ILLINOIS, ASSIGNOR TO SEARS, ROEBUCK AND COMPANY, OF CHICAGO, ILLINOIS, A CORPORATION OF NEW YORK.

RETAINER-BAR FOR WARDROBE-TRUNKS.

1,186,045.

Specification of Letters Patent.

Patented June 6, 1916.

Application filed December 17, 1914. Serial No. 877,728.

To all whom it may concern:

Be it known that I, PAUL C. SCHROEDER, a citizen of the United States, residing at Chicago, in the county of Cook and State of Illinois, have invented certain new and useful Improvements in Retainer-Bars for Wardrobe-Trunks, of which the following is a specification.

Heretofore the retainer-bars of wardrobe trunks have been so constructed that in order to release the clothing it has been necessary to remove the retainer-bar bodily from the trunk. In replacing the retainer-bar it was necessary to attend particularly to the matter of properly associating the ends of the bar with the coöperating devices in the trunk. It was also necessary to manipulate the locking devices that secured the retainer-bar at the desired place in the trunk.

Among the objects of my invention are to obviate the necessity of removing the retainer-bar from the trunk, and to provide a locking means for locking the retainer-bar in contact with the clothing, said locking means being operable in the simple act of placing the bar in the desired position.

In the accompanying drawings, Figure 1 is a fragmental perspective view of one section of a wardrobe trunk showing my improvements applied thereto. Fig. 2 is a transverse horizontal sectional view of said trunk section. Figs. 3 and 4 are fragmental sectional views taken in the plane of dotted line 3—3 of Fig. 5 and illustrating the operation of the locking means. Fig. 5 is a view looking from the left-hand side of Fig. 3.

A denotes a section of a wardrobe trunk. Upon the inner longitudinal walls of said trunk section are fixed two guide bars 1, upon which the retainer-bar 2 is slidable toward and away from the bottom or back of the trunk section. The bar 2 consists of two hinged sections, the adjacent ends of the sections being arranged to be locked together in alinement by means of a latch 3 of any ordinary or preferred construction. When the latch 3 is opened, the two sections of the bar 2 may be swung apart (as indicated by the arrows in Fig. 2) for the insertion or removal of clothing from the trunk.

Inasmuch as the locking devices at the opposite ends of the bar 2 are identical, it will be sufficient to describe one of them.

The end of the bar section is secured to a bracket 4, which is pivotally connected by means of a pin 5 to a slide 6. The slide 6 is movable lengthwise of the guide bar 1. Said slide carries a clamp member 7 having an opening 7^a through which the guide bar 1 extends. The clamping member 7 has an angular lug 11 which extends loosely through an opening 8 in the slide 6. The clamping member 7 is adapted to have a limited pivotal movement in the opening 8.

9 is a coiled spring surrounding the guide bar 1 and interposed between a portion of the slide 6 and the clamping member 7.

10 is an angular lug on the inner end of the bracket 4, said lug being adapted to engage the lug 11 and move the clamping member 7 into inoperative position.

Figs. 1, 2 and 3 illustrate the position of the parts when the retainer-bar 2 is locked on the guide bars 1. When the latch 3 is released and the sections of the retainer-bar are swung apart, the lugs 10 engage the lugs 11 and tilt the clamping members 7 so as to disengage said members from the guide bars 1. After the desired changes have been made in the contents of the trunk, the slides are pushed inwardly to an extent corresponding to the thickness of the layer of clothing, and the two sections of the retainer-bar are then swung together and secured by means of the latch 3. In the operation of swinging the sections of the retainer-bar toward each other the clamping members 7 are automatically actuated by the springs 9 to clamp the slides 6 on the guide bars 1. As indicated in Fig. 3, the edges of the walls of the openings 7^a frictionally engage the bars 1 to prevent outward movement of the slides 6.

It will be seen that the retainer-bar remains attached at all times to the trunk; that it may be readily operated to release the clothing; and that no particular attention is required in locking the bar against outward movement.

I claim as my invention:

1. In a trunk, the combination of a casing, two members slidable in said casing, two retainer-bar sections, each pivoted at one end to one of the slidable members, a latch for joining the opposite ends of said sections, and means for locking the slidable members against movement.

2. In a trunk, the combination of a casing, two retainer-bar sections each movably connected at one end to the casing, means for holding said sections in substantial alinement, and means for locking the alined sections against movement in one direction. 25
3. In a trunk, the combination of a casing, guide-bars at opposite sides of said casing, a slide on each guide bar, two retainer-bar sections, each pivoted at one end to one of the slides, means to hold said sections in substantial alinement, and means arranged to engage the guide bars to lock the slides against movement in one direction. 30
4. In a trunk, the combination of a casing, guide bars at opposite sides of said casing, a slide on each guide bar, two retainer-bar sections, each pivoted at one end to one of the slides, means to hold said sections in substantial alinement, a clamping member pivoted on each slide and arranged to engage the adjacent guide bar, springs tending to move the clamping members into operative position, and means actuated by the re- 35

tainer-bar sections for moving the clamping members into inoperative position.

5. In a trunk, the combination of a casing, guide bars at opposite sides of said casing, a slide on each guide bar, two retainer-bar sections, each pivoted at one end to one of the slides, means for holding the sections in substantial alinement, a clamping member pivoted on each slide and arranged to engage the adjacent guide bar, springs tending to move the clamping members into engagement with the guide bars, each clamping member having a lug, and a lug on each retainer-bar section arranged to engage the lug on the adjacent clamping member for moving said clamping member into inoperative position. 40

In testimony whereof, I hereunto set my hand in the presence of two witnesses.

PAUL C. SCHROEDER.
